UNITED STATES PATENT OFFICE.

ISAAC S. ALTON, OF OXFORD, KANSAS.

ELEVATOR DUMP.

Application filed September 25, 1922. Serial No. 590,502.

To all whom it may concern:

Be it known that I, ISAAC S. ALTON, a citizen of the United States, residing at Oxford, in the county of Sumner and State of Kansas, have invented certain new and useful Improvements in Elevator Dumps; and I do declare the following to be a full, clear, and exact description of the invention, such as will enable others skilled in the art 10 to which it appertains to make and use the same.

My invention relates to improvements in dumps and more particularly to one designed primarily for dumping grain at elevators, one object being to provide a dump having two receiving openings preferably spaced different distances from a wagon or truck hoist, whereby wagons may be dumped by the hoist into one opening and trucks 20 dumped into the other opening, novel provision being made for discharging the dumped grain or other material into either or both of a pair of receiving chambers, regardless of the opening into which the dumping 25 is done.

With the foregoing in view, the invention resides in the novel subject matter herein-after described and claimed, the description being supplemented by the accompanying 30 drawings.

Figure 1 is a top plan view of a dump constructed in accordance with my invention.

Figure 2 is a longitudinal vertical section as indicated by line 2—2 of Fig. 1. 35 In the drawings above briefly described, the numeral 1 designates an elevated platform at one end of which I intend to place a hoisting device (not shown) for dumping wagons and trucks driven onto the platform, 40 this platform being provided with an opening 2 into which wagons may be dumped and an opening 3 more remote from the hoist, to receive the contents of trucks. A pair of chutes 4 incline in opposite directions from the openings 2 and 3 and are preferably narrowed toward their lower ends by being provided with oblique side boards 5 at their adjacent sides, whereby the lower ends of the chutes may cross each other to discharge at 45 opposite sides of a vertical partition 6, into a pair of receiving chambers 7.

The upper end of each trough 4 is pro-

vided in its bottom with an opening 8 and a pair of removable closures 9 are provided for the two openings, said closures 55 resting upon the bottoms of the troughs and being held against downward sliding by suitable cleats 10 secured to said bottoms. When it is intended that the grain or the like shall slide throughout the length of one 60 trough or the other, its closure 9 remains in the full line position shown in Fig. 2. However, if either trough or chute is to discharge into the receiving chamber 7 ordinarily fed by the other chute, its closure 9 is removed and positioned across the chute, at the lower edge of its opening 8, as shown by dotted lines in Fig. 2. In this position, the upper portion of the closure 9 may well rest against one edge wall of the openings 2 or 3, while 65 its lower end is supported by the bottom of the chute and bears against the upper edge of the cleat 10. Thus, instead of the material sliding throughout the length of the chute, it will merely fall through the opening 70 75 thereof.

From the foregoing, taken in connection with the accompanying drawings, it will be seen that a simple arrangement has been provided whereby either wagons or trucks 80 may be readily dumped and whereby the contents of either may be distributed as required in the two receiving chambers 7.

As excellent results may be obtained from the details disclosed, they are preferably 85 followed, but within the scope of the invention as claimed, numerous minor changes may of course be made.

I claim:

1. A distributing dump comprising a platform having spaced openings, a partition beneath said platform and between said openings, chutes extending from said openings in opposite directions and extending across said partition for depositing material upon the opposite sides of the partition, each chute having an opening beneath the opening in the platform from which the chute extends, and a cover movable from a lowered position closing the opening to an elevated position forming a barrier extending across the chute for directing material through the opening in the chute. 95

2. The structure of claim 1 having each

chute provided with means for engaging the lower end of the cover for the opening in the chute and supporting the cover.

3. A distributing dump comprising a platform having spaced openings positioned opposite each other, a partition beneath said platform and between said openings, and chutes extending from said openings in

opposite directions and having their lower portions tapered and extending side by side ¹⁰ in overlapping relation across said partition.

In testimony whereof I have hereunto affixed my signature.

ISAAC S. ALTON.
